UNITED STATES PATENT OFFICE.

D. P. WEBSTER, OF UPPER GILMANTON, NEW HAMPSHIRE.

IMPROVED SPRING BED-BOTTOM.

Specification forming part of Letters Patent No. 57,229, dated August 14, 1866.

To all whom it may concern:

Be it known that I, D. P. WEBSTER, of Upper Gilmanton, Belknap county, and State of New Hampshire, have invented a new and Improved Spring-Bed; and I do hereby declare that the following is a full, clear, and exact description thereof, which will enable others skilled in the art to make and use the same, reference being had to the accompanying drawings, forming part of this specification, in which—

Figure 1 represents a longitudinal vertical section of this invention. Fig. 2 is a transverse section of the same.

Similar letters of reference indicate like parts.

This invention relates to a spring-bed of that class in which a series of flexible slats are supported by the large ends of conical springs; and the invention consists in the arrangement of a clamp which catches over the flexible slats and under the upper coils of the springs in such a manner that said upper coils are securely fastened to the slats and that a spring-bed is obtained which makes no noise and which is durable and not liable to get out of order.

A represents a bed or frame, which is composed of longitudinal bars *a* and cross-bars *b*. The cross-bars *b* serve to support the conical springs *c*, which are placed with their large ends up and which support the slats *d*. These slats are made of wood or other flexible and elastic material, and each slat rests on two or more springs, two springs being sufficient for all practical purposes.

The upper coils of the springs are secured to the slats by clamps *e*, the ends of which are turned into hooks *f*, which are slipped over the slats and catch under the coils of the springs, as clearly shown in Fig. 2 of the drawings, so that said coils are drawn up close to the slats, and the slat is not liable to knock against the coil and to produce a disagreeable noise.

The clamps *e* are easily made, they are readily attached or detached, and by their use a cheap and durable spring-bed is obtained, which obviates all the disadvantages of other spring-beds of a somewhat similar construction, in which the springs are secured to the slats by eyes formed by the ends of the springs themselves. Such beds are liable to make a noise, because the upper coils of the springs are not drawn up close to the slats; and, furthermore, the operation of securing the slats to the springs is tedious and not easily accomplished.

What I claim as new, and desire to secure by Letters Patent, is—

The single wire clamp *e*, with its hooks *f* catching under the top coil of the spring and holding it up against the slat, substantially as described, for the purpose specified.

The above specification of my invention signed by me this 6th day of July, 1866.

D. P. WEBSTER.
